UNITED STATES PATENT OFFICE.

PAUL A. WAGNER, OF JERSEY CITY, NEW JERSEY.

DYING MACHINE.

Application filed January 11, 1922. Serial No. 528,395.

To all whom it may concern:

Be it known that I, PAUL A. WAGNER, a citizen of the United States, residing at Jersey City, in the county of Hudson and 5 State of New Jersey, have invented a certain new and useful Improvement in Dyeing Machines, of which the following is a specification.

The invention relates to mechanism for 10 supporting the material to be dyed, presenting it to the dyeing liquor, and removing it therefrom, and is intended especially for treating yarns and the like in skeins.

The main object of the invention is to provide 15 a power driven machine adapted to serve with a multiplicity of skein-carriers and the usual dye tank, and perform the dyeing operations in a manner closely analogous to hand-dyeing, and capable of treating 20 large quantities of material economically, expeditiously and efficiently with but little labor and in relatively small space.

Another important object is to provide 25 means whereby the loaded skein-carriers may be grouped in close relation to each other in the tank, or transferred and accumulated idly above the tank for removal or for permitting the dye to be acted upon by the air as in the oxidizing processes, or for permitting 30 free access to the tank.

A further object is to provide simple, 35 automatically operated means whereby the carriers may be turned to present new portions of the skeins to the action of the liquor, and another important object is to provide means for automatically removing excess liquor from the skeins during the passage 40 of the carriers from the tank.

The invention consists in certain novel features of construction and arrangement by 45 which the above and other objects are attained, to be hereinafter described and claimed.

The accompanying drawings form a part 45 of this specification and show an apparatus capable of carrying out the invention.

Figure 1 is a side elevation of the machine, showing the skeins accumulated in the tank.

50 Figure 2 is a corresponding plan view.

The remaining figures are on a larger scale and show details of the skein moving mechanism.

Figure 3 is an edge view of a portion of one of the carrier belts. 55

Figure 4 is a corresponding face view.

Figure 5 is a vertical section through one end of one of the skein-carriers, and partly in elevation.

Figure 6 is a vertical section partly in elevation, showing a means for turning the carriers successively. 60

Similar reference numerals indicate the same parts in all the figures.

The tank 10 containing the dye liquor may 65 be the usual rectangular vat used in the common hand dyeing processes with the top edges of its sides adapted to support the skein-carriers, and on each side of the tank are vertical standards 11 carrying the mechanism 70 by which the skeins are introduced to and removed from the liquor.

The standards at one end of the tank are taller than those at the other and are joined above by an inclined beam 12 well outside 75 the tank on one side thereof, and a beam 13 similarly located on the other side. Joined to the beams by horizontal braces 16 are rails 14 and 15 parallel with but shorter than the beams. In plan view the rails lie close 80 in line with the side-walls of the tank, and like the latter are adapted to support the skein-carriers.

Below the beams 12 and 13, at each end and in line therewith, are short horizontally 85 disposed bars 17 and 18 supported by the standards at a level a little above the tank.

The standards, beams, rails, and bars, with certain additional parts, constitute the frame 90 of the machine and are independent of the tank.

On the outer face of the beam 12 is a main shaft 19 slidably mounted in bearing brackets 20 and arranged to be moved axially by a shifting-lever 21 controlling a shifting-mechanism 22 only partially shown. Fixed 95 on the shaft near its ends are mitre pinions 23 and 24; one, marked 23, adapted to mesh with a mitre gearwheel 25 on a transverse shaft 27 at one end of and above the tank, supported in bearings 28 on the under faces of the beams, a similar shaft 26 is mounted in bearings 28 at the other end of the beams but carries no mitre gearwheel. The lower end of the inclined main shaft 19 carries a 100 spur gearwheel 29 in mesh with a long pin-

ion 30 on the shaft 31 of a motor 32. The motor shaft 31 is at the same inclination as the main shaft 19, and its pinion 30 is of sufficient length to permit the gearwheel 29 5 to shift with the longitudinal movements of the main shaft while still maintaining engagement.

Mounted in bearings on the under faces of the beams and rails, on each side and at 10 each end above the tank are four short shafts 33, 34, 35 and 36 each carrying a spur gearwheel 37 adjacent the beam and a double sprocket wheel 38 adjacent the rail. The gearwheels 37 are in mesh with similar gearwheels 39 on the shafts 26 and 27. One of the short shafts, marked 33 extends beyond its beam 12 and is equipped with a mitre gearwheel 40 adapted to mesh with the mitre pinion 24 above mentioned. Each of the 15 short shafts 33 and 34 carries a pulley 41.

The mitre pinions 23 and 24 are each located beyond its mitre gearwheel 25 or 40 and by shifting the shaft 19 either mitre pinion may be engaged with its mitre gearwheel, or both may revolve idly out of mesh with such gearwheels. This arrangement permits the mechanism to be driven either through the shaft 27 at one end or the short shaft 33 at the other, and always in the 20 same direction.

The skein carriers are preferably thin slats 42 of wood, each of a length somewhat less than the interior width of the tank, and having a width or depth considerably 25 greater than the thickness. The upper and lower margins of the faces are beveled on curves, as in Figures 3, 5 and 6, to produce bluntly sharpened edges 43, and at the ends near the upper edge are hollow extensions 30 or trunnions 44 adapted to lie upon the upper faces of the side walls of the tank and support the skeins suspended in the dye liquor or upon the rails 14 and 15.

A pair of long flexible endless belts composed of links 45 hinged each to the next at 46 run over the double sprocket wheels 38 above, and under similar sprocket wheels 47 and 68 mounted beneath the bars 17 and 18 at each end of and immediately above the 50 tank. Between each slat 42 and the next succeeding, the pintles for the link hinges are short studs 48 inclosed by the hinge members and projecting on each side of the belt, and the trunnions 44 are separably 55 joined to the link hinges by pins 49 extending like the studs 48 through the hinge members with their reduced inner ends 50 received in the axial cavities in the ends of the trunnions as shown in Figure 5. An annular groove 51 on the reduced portion receives the nose 52 of a spring-catch 53 mounted on the trunnion and holds the pin 49 against withdrawal until the nose is lifted. The 60 studs 48 and trunnions 44, 49 engage with the teeth on the double sprocket wheels, and

the links of the belt lie between the toothed members of such wheels.

The construction of each belt is such that the links thereof are capable of expanding and collapsing, that is they may fold so as 70 to be disposed substantially parallel with each other, as seen in their position when the skeins are in the tank in Figure 1, and then they stretch out or expand so as to extend in line with each other, like the links 75 of an ordinary chain, when passing upward from one end of the tank, across the rails above the tank and then downwardly at the entrance end, when they automatically fold or collapse by their own weight.

The carriers extend transversely from one belt to the other and the trunnions thereon with the studs 48 are so spaced as to match to the spaces between the teeth of the sprocket wheels, and the paths of the belts 85 lie in lines outside the tank. Four links with their studs lie between each pair of carriers on each side and the slack of the belts is such that the carriers may be placed close together across the tank with the links 90 depending idly in loops on each side, as in Figure 1, or similarly accumulated on the rails 14, 15 above as will be understood, and a sufficient number of succeeding carriers are left unloaded during the dyeing 95 operation to permit all the loaded carriers to be thus grouped while the unloaded carriers lie distributed idly along the paths of the belts, the latter being sufficiently longer than such paths to afford the required slack.

The belts move in the direction indicated by the arrows in Figure 1. In the upward movement of the carriers from the tank to the sprocket wheels 47 and thence to the sprocket wheels 38 provisions are made for 105 wringing or removing the dye liquor from the skeins; this portion of the apparatus consists of a roller 54 mounted in brackets 55 projecting downwardly from the rails 14 and 15 and driven by a belt 56 from a pulley 57 on the shaft 35, in conjunction with a similar roller 58 mounted in a swinging frame 59 fulcrumed in brackets 60 on the bars 17, and arranged to be swung by a cam 61 operated by the hand lever 62 by which 110 the roller 58 is brought into wringing contact with the relatively fixed roller 54. The beveled edges 43 of the carriers permit their easy entrance to and egress from the rollers, and the skeins hung thereon will be squeezed 115 in their upward passage as will be understood. The size of the pulley 57 and the pulley on the roller shaft are so proportioned as to revolve the rollers at a rate slightly faster than that of the carriers 42 and their 120 skeins so that the latter will not be subjected to pulling strains in the wringing operation.

At the opposite end of the machine is a device for turning the carriers successively on the trunnions 44 to change the positions 125

of the skeins carried thereon to a new point of suspension in the several skein-loops and thus insure uniform treatment throughout. The mechanism shown consists of a fixed 5 channel 63 having a series of equally spaced transverse pins 64 adapted to engage the teeth of a star wheel 65 fixed on the trunnion 44 at one end of each carrier and cause the carrier to make a little more than a half 10 revolution in its descent from the sprocket wheels 38 at the front. The weight of skeins is sufficient to complete the revolution and suspend the skeins by a new portion.

The pulleys 41 on the short shafts 33 and 15 34 carry belts 66 running on pulleys 67 on the shafts of the sprocket wheels 68 below thus rotating the sprocket wheels 68 and serving to push each carrier forward along 20 the tank and thus move the whole group of carriers along the tank at each accession of a carrier.

In operating the machine for continuous treatment the pinion 24 of the main shaft is thrown into mesh with the mitre gear- 25 wheel 40 on the short shaft 33 by which the sprocket wheels 38 at that end of the tank are revolved and the carriers drawn down the inclined rails 14 and 15 and fed downwardly past the turning mechanism to the 30 sprocket wheels 68, driven as above described, and pushed along the side walls of the tank, correspondingly crowding forward any previously delivered carriers, and drawing the carriers successively from the oppo- 35 site end of the tank to make the circuit again. In this operation the skeins of each carrier are in contact with the liquor during the slow traverse of the tank and are then quickly returned for a succeeding trav- 40 erse, and all the carriers may be loaded. The excess liquor may be wrung out or not as preferred; the skeins are always within the confines of the tank and the liquor may drip freely therein and it will be observed that 45 the skeins contact only with the carriers and the dye liquor.

A sufficient number of successive carriers may be left unloaded to permit the belts to extend idly through their paths from the 50 egress end of the tank and along the rails 14 and 15 to the ingress end, as in the drawings, and the machine driven as above until all the loaded carriers are accumulated in the tank with their skeins suspended in the 55 liquor. The main shaft is then shifted to the neutral position to stop the rotation of the sprocket wheels, and the skeins subjected to the action of the liquor as long as may be desired.

60 By shifting the main shaft to engage the pinion 23 with the mitre gearwheel 25 on the shaft 27, the sprocket wheels 38 at the egress end of the tank will be rotated and all the loaded carriers accumulated on the 65 inclined rails 14 and 15 with the unloaded

carriers occupying the remainder of the belt-paths. When the apparatus is used in this manner the skeins are subjected to the action of the wringing mechanism in their ascent and are then held suspended above 70 the tank exposed to the air in carrying out the oxidizing process. With the apparatus thus conditioned the tank and its contents are readily accessible.

In loading or unloading, the carriers are 75 freed at one or both ends by releasing the spring-catch 53 and removing the pins 49 from the trunnions 44 either by withdrawing the pins completely or by distorting the belts laterally to the extent necessary to 80 free the ends of the pins from the trunnions.

It will be noted that the invention is applicable to the usual dyeing tanks and that the mechanism occupies but little additional space. The operation is practically auto- 85 matic requiring but little labor by the attendant, and is closely analogous to the successful hand-dyeing processes.

The belts and their studs are outside the tank in all positions and by reason of their 90 flexibility the loaded carriers may be massed side by side as above described, permitting the whole length of the tank to be utilized, thus greatly increasing the capacity of the machine, and the operation may be rapid 95 while permitting long immersion during the slow traverse of the carriers from one end of the tank to the other.

Modifications may be made in the details 100 of the mechanism within wide limits without departing from the principle of the invention or sacrificing its advantages. The structure of the belts may be varied and also the sprocket wheels and driving mechanism therefor. The wringing device and also the 105 turning device may be omitted or their functions performed by other means than those shown and described.

I claim:

1. In an apparatus of the character set 110 forth, a pair of flexible belts, and a series of skein-carriers mounted to travel therewith, said belts adapted to collapse between adjacent carriers.

2. In an apparatus of the character set 115 forth, a pair of flexible endless belts, a series of skein-carriers mounted to travel therewith, and supporting means for said carriers engaged by the ends of the latter, said belts adapted to collapse between adjacent 120 carriers and lie outside such supporting means.

3. In an apparatus of the character set 125 forth, a tank, a pair of flexible endless belts arranged to travel in endless parallel paths above said tank, and a series of skein-carriers mounted in said belts to travel therewith, said belts of greater length than such paths, whereby a portion of said carriers may be collapsed and accumulated in close 130

relation to each other in portions of such paths.

4. In an apparatus of the character set forth, a tank, a pair of flexible endless belts, 5 a series of spaced skein-carriers mounted in said belts to travel therewith in endless paths extending forwardly along said tank, upwardly at one end of said tank, rearwardly along rails above said tank, and 10 downwardly to the tank, said belts of greater length than such paths, whereby a proportionally great number of said carriers may be accumulated in close relation to each other along said tank or upon said rails.

15 5. In an apparatus of the character set forth, a tank, an endless carrier for the skeins, said carrier having members automatically expansible as they change their path from a horizontal to a vertical direction, and means for wringing the material 20 while said members are in their expanded condition.

6. In an apparatus of the character stated, a tank, and an endless skein carrier 25 composed of links hingedly united for automatic expansion and contraction to vary the length of the carrier.

7. In an apparatus of the character set forth, a tank, a pair of flexible endless belts, 30 and a series of skein-carriers removably mounted in said belts to travel therewith, said belts adapted to collapse between adjacent carriers.

8. In an apparatus of the character set forth, a tank, a pair of flexible endless belts, 35 and a series of skein-carriers mounted in said belts to travel therewith with their skeins within said tank, said belts adapted

to collapse between adjacent carriers and arranged to lie outside said tank in such 40 collapsed condition.

9. In an apparatus of the character set forth, a tank, a pair of flexible endless belts, a series of skein-carriers mounted in said belts to travel therewith with their skeins 45 within said tank, said belts adapted to collapse between adjacent carriers and arranged to lie outside said tank in such collapsed condition, and means for moving 50 said carriers along said tank with said belts thus collapsed.

10. In an apparatus of the character set forth, a pair of flexible endless belts, a series of skein-carriers mounted in said belts to travel therewith, means for moving said 55 belts, and means for supporting said carriers auxiliary to said belts, the latter adapted to collapse between adjacent carriers and having sufficient slack to permit an accumulation of said carriers in close relation to each other on such supporting means.

11. The carrier described consisting of a slat having greater depth than thickness and having projecting trunnions at its ends 60 adapted to be connected to a means for holding and moving such carrier and in rotatable engagement with said means.

12. The carrier described consisting of a slat having greater depth than thickness 65 and its upper and lower edges beveled, and having trunnions at its ends near such upper edge.

In testimony that I claim the invention above set forth I affix my signature.

PAUL A. WAGNER.
